GATE LATCH

Benjamin Heyman, Baltimore, and Francis K. Read, Pikesville, Md., assignors to Anchor Post Products, Inc., a corporation of New Jersey

Application May 10, 1951, Serial No. 225,592

6 Claims. (Cl. 292—8)

1

This invention relates to a gravity-actuated gate latch which locks in a uniform and positive manner as the gate is closed.

In carrying out our invention, we provide a rotatively mounted gate latch of simple and economical construction with a striker which hits the latch and lifts it up as the gate is closed. Gravity then makes the latch fall back over the striker to lock the gate. Uniform and positive locking is insured by a cam or projection on the latch which contacts the striker and assists gravity in closing the latch. This cam so accelerates locking action that the latch is closed before the striker can rebound and escape the latch even when the gate is slammed shut.

The nature of this invention may be readily understood by reference to the example shown in the accompanying drawing in which Fig. 1 is a top plan view of our improved gate latch; Fig. 2 is a front elevational view taken on line 2—2 of Fig. 1; Fig. 3 is a similar view showing the camming action of the latch, and Fig. 4 is a perspective view showing a form of gate latch as applied to a double-swing gate.

In the drawings, latch 10 is rotatively mounted by swivel bolt 12 on a door frame or stationary gate post 14. As best shown in Fig. 1, free rotation of latch 10 about swivel bolt 12 is insured by spacer bushing 16 and washers 18. Bushing 16, tightly fitted in latch 10, is of somewhat greater length than the thickness of the latch and its inside diameter is greater than the diameter of bolt 12. Thus washers 18 are held away from latch 10 and bolt 12 may be drawn tight without binding the latch. The top portion of each end of latch 10 is flared to form a pair of operating handles 20 and 22 provided with stop faces 24 and 26. These stop faces make contact with post 14 and keep rotation of latch 10 within working limits. Latch 10 has most of its weight to the left of swivel bolt 12 and thus stop face 26 ordinarily makes contact with gate post 14. This holds latch 10 approximately horizontal in readiness to receive striker 28 (see Fig. 2).

Striker 28 is securely mounted on gate post 30 as by bolt 32 so that it will engage notch 34 of latch 10 for locking the gate. In the example of our invention shown striker 28 has lateral extensions 36 and 38 on either side of gate bearing surface 40 which grip post 30 and provide a firm support for the striker (see Fig. 1).

When the gate is closed, striker 28 hits inclined surface 42 of latch 10. This lifts latch 10 and gravity then tends to close it, to lock striker 28 in notch 34. To insure positive action of latch

2

10, we provide it with a projection or cam face 44. When latch 10 is lifted, cam 44 extends beyond the limits of post 14 where striker 28 hits it to assist gravity in closing the latch (see Fig. 3). This prevents any tendency for the gate to bounce open because striker 28 cannot rebound until after latch 10 is closed.

The gate may be conveniently opened from either side of the fence with handle 20 or 22. Hole 46 in latch 10 is adapted to receive a padlock shackle or the like which prevents lifting the latch.

In the form of our invention shown in Fig. 4 the left gate member 48 carries striker 50, similar to striker 28 previously described, and the right gate member 52 carries latch 54 corresponding to latch 10. Drop bar 56, slidably mounted by brackets 58 on gate member 52, is positioned with handle 60 immediately below latch 54 where it will not interfere with the latch. Drop bar 56 extends into a usual well 62 to hold gate member 52 closed. Latch 54 has a hole 64 corresponding to hole 46 to be used for locking the gate shut.

25 When gate member 48 is closed, the gates are locked and drop bar 56 is also locked in well 62. The drop bar cannot be turned because of gate members 48 and 52 and it cannot be lifted because it hits striker 50. As shown in dotted lines, drop bar 56, when not in use, may be conveniently placed behind projection 66 of latch 54 where it is held out of contact with the ground. If desired, the bar may be dropped at any time to hold gate 54 in an intermediate position.

30 It will be understood that it is intended to cover all changes and modifications of the preferred embodiment of this invention herein chosen for the purpose of illustration which do not constitute departures from the spirit and scope of the invention.

40 What we claim is:

1. In a latch member of the type described including a post for mounting said latch member and a swinging gate with a striker thereon, 45 the combination of a latch member adapted to cooperate with the striker for locking the gate, a notch in the lower face of said latch member near one end, said notch having a surface wall which lies in a substantially vertical plane taken 50 through the width of the latch member when said member is in position to receive the striker, an inclined surface extending upwardly from said notch, means for rotatively mounting the latch member, said inclined surface being adapted 55 to cooperate with the striker to lift the latch.

member whereby the striker is locked in said notch as the gate is closed and said latch member having its top portion at each end flared to form a pair of operating handles which extend outwardly from the body of the latch member at an approximate right angle for operating the latch member on either side of the gate, said handles being adapted to cooperate with the latch member mounting post to limit rotation of the latch member and keep it within working limits.

2. A structure as specified in claim 1 in which the latch member has a cam surface associated with said notch and adapted to cooperate with the striker to assist in closing the latch member.

3. A structure as specified in claim 1 in which the mounting means include a bushing of slightly greater length than the thickness of the latch member adapted to cooperate with a bolt for mounting the latch member whereby the bolt 20 may be drawn tight without binding the latch member.

4. A structure as specified in claim 1 which includes a projection extending upwardly from the top of said latch member, said projection 25 being adapted for receiving a hasp to prevent lifting the latch.

5. In a device of the type described the combination of a latch member and a drop bar adapted to cooperate with a striker for locking 30 a pair of swinging gates, a notch in the lower face of said latch member near one end, said notch having a surface wall which lies in a substantially vertical plane taken through the width of the latch member when said member is in 35 position to receive the striker, an inclined surface extending upwardly from said notch, means

5
10

for rotatively mounting the latch member on one of the gates, a stop to limit latch rotation, means for slidably mounting the drop bar on the same gate below the latch member, said drop bar being adapted to hold the gate in a set position, means for mounting said striker on the other gate in position to cooperate with the inclined surface of the latch member to lift the latch member whereby the striker is locked in said notch when the gates are closed and said drop bar having a handle positioned adjacent to the bottom edge of the locked striker which prevents lifting the bar.

6. A structure as specified in claim 5 which includes a projection extending upwardly from the top of said latch member, said projection being adapted for receiving a hasp to prevent lifting the latch member and for carrying the bar when it is not in use below the striker.

BENJAMIN HEYMAN.
